ELEVATOR CONTROL MECHANISM

George D. Pettengill, Thomas F. Jarvis, and William L. Fader, Warsaw, N. Y., assignors to Warsaw Elevator Co., Warsaw, N. Y.

Application October 2, 1947, Serial No. 777,396

11 Claims. (Cl. 318—210)

1

This invention relates to improvements in electrically powered elevator drive mechanisms; the term "elevator" as used herein being intended to relate to passenger and/or freight carrying elevators traveling within hatchways between relatively closely spaced stations and operating under conditions requiring relatively high acceleration-deceleration performance.

Whereas the characteristics of previous type elevator drive mechanisms made it preferable to employ relatively low speed single speed or two-speed alternating current motors or direct current motors with suitable speed control accessories, such motors and control equipment are relatively costly compared to standard type higher speed (single speed) alternating current motors. Such "standard" motors are unsuited for use in connection with the prior elevator drive designs because of their slow-down characteristics when high speed elevator performance is prescribed. Hence, it has heretofore been necessary to employ the more expensive types of motors and speed control accessories for elevator drive purposes. Another disadvantage attendant the use of such prior elevator drive designs is that they do not lend themselves to good advantage to certain braking techniques such as would reduce the friction-braking requirements on the drive system incidental to service stops and automatic leveling procedures.

It is an object of the present invention to provide an improved type of elevator electric drive and braking mechanism which embodies an improved motor and traction sheave interconnection means of such character as to provide overall improved elevator car starting acceleration and braking deceleration characteristics, while employing the most economical type electric motor and speed reduction gear devices.

Another object of the invention is to provide an improved elevator drive mechanism which provides a smoother starting operation while imposing lower inrush currents on the driving motor windings.

Another object of the invention is to provide a new and improved type elevator drive mechanism which supplies a novel and improved braking action for stopping the elevator car.

Another object of the invention is to provide a unique application and development of "electric braking" principles in elevator drive devices.

Another object of the invention is to provide a unique and improved elevator driving and braking mechanism which is of such character as to eliminate the need for frictional braking means

2

to bring the elevator car to a stop, whereby only a relatively light duty frictional brake need be supplied for holding the car while at rest.

Another object of the invention is to provide an improved elevator driving and braking system which is fully controllable through means of a simplified control arrangement.

Another object of the invention is to provide a new and improved driving motor coupling arrangement in electrical elevator drives and the like, whereby to obtain smoother starting and stopping of the elevator car.

Other objects and advantages of the invention will appear from the specification hereinafter.

In order to attain the objects and advantages set forth hereinabove the invention contemplates an elevator drive unit comprising a relatively low cost single winding type A. C. motor of suitable horsepower; a traction type torque transmitter

20 connecting the motor to the load; an elevator traction sheave or drum; suitable "holding" friction brake means acting upon means geared to the traction wheel; and where necessary, a suitable speed reduction gear unit interconnecting the driven portion of the torque transmitter and the traction sheave. Within the concept of the present invention it is essential that the motor be adaptable to A. C. plugging service, that is; it may be suddenly reversed as to phase relation, 30 and that the torque transmitter be adapted to "slip" while the motor is coming up to speed so as to avoid excessive inrush of starting currents through the motor windings, and to avoid uncomfortable acceleration of the elevator car.

35 It is also essential that the torque transmitter be of such nature as to impose high drag forces from the plugged motor upon the traction sheave system during the initial high speed stage of elevator car deceleration preliminary to a stopping operation; and it is further essential, for the purposes of the invention, that the torque transmitter be designed to impose relatively low drag forces upon the traction sheave during the later stages of elevator car deceleration, incidental to a stopping operation.

In some cases such as where the inertia forces of the moving elevator system are relatively great it may be desirable to provide for the motor to operate in reverse direction during the final stage 50 of elevator car deceleration, but in any case the invention contemplates a novel motor torque control system which obtains final stopping of the elevator car through an improved form of "electrical braking," thereby requiring only a minimum duty frictional braking device for "holding"

purposes only. The torque transmitter may be of some suitable traction type, such as for example a "fluid coupling" device employing the hydro-kinetic principle or a hydraulic system of the torque converter type, or an electromagnetic clutch, or a suitable variable slip mechanical clutch, or the like. However, we presently prefer to employ for this purpose a "fluid coupling" device because of its mechanical simplicity and ruggedness and economy and ease of operation, as well as because of its operational characteristics which so particularly adapt it to the problem as will be explained more fully hereinafter.

Referring now to the drawing, the single figure is a diagrammatic representation of an elevator driving and braking and control mechanism embodying the invention; and as illustrated therein the elevator car 10 is suspended by a cable 12 running over a traction sheave 14 and counter-weighted at its opposite end as indicated at 16. The traction sheave 14 is fixed to a shaft 18 which is in turn fixed to gear 20 meshing with a worm 22. The worm 22 is driven by a shaft 24 which connects at its other end to the driven element of a traction coupling device which is illustrated generally at 25. The driving element of the traction coupling 25 is fixed to the armature shaft 26 of the elevator driving motor 30. The motor 30 is illustrated herein to be of the three-phase single speed A. C. type, and an electromagnetically actuated friction brake 32 is shown as being applied to the drive shaft 24.

In the drawing the circuits carrying power to the motor 30 are shown in heavy lines, commencing with supply mains 34-35-36 and thence leading through circuit controlled relays, the operation of which will be explained fully hereinafter. It will of course be understood that the invention is applicable to various types of driving motors and control systems, and that the drawing herein purposely illustrates only a relatively simple or "basic" motor control system providing minimum elevator control features. Thus, the drawing herein shows a control system embodying the usual hatchway door contact switches; an elevator car gate switch; an elevator speed governor switch; normal limit switches; terminal limit switches; a car safety switch, and the usual manual control switch in the elevator car. However, further accessory features may be readily added to the control system shown in the drawing herein as will be readily understood by those skilled in the art, so as to include for example automatic operation from hall buttons, automatic leveling, automatic door operation, and so on.

Referring again to the drawing; whereas the power circuits are shown in heavy lines, the control circuits are shown in lighter lines, and the manual car control switch is indicated at 40 as comprising a lever pivotally mounted on the elevator car wall. The lever 40 carries a conducting segment 42 which, when the lever is in its neutral position interconnects contact terminals 44-46-48 of the control circuit. Commencing at the lower left hand corner of the drawing, it will be seen that a control circuit feed is picked up from supply main 35 by a control conductor 50 which includes in series therewith an appropriate number of hatchway door contact switches, depending upon the number of doors in the hatchway. In the drawing, for purposes of illustration, it is indicated that there are three doors in the hatchway equipped with door contact switches, as indicated at 52-53-54, respectively. The conductor 50 also includes the elevator car gate con-

tact switch 55 and then terminates at a normally open terminal 56 of a sequence control switch 60. The switch 60 is actuated by a relay coil 62 as will be explained hereinafter.

The second control circuit feed originates at supply main 36 and leads therefrom through conductor 64 and through the usual governor switch 65, and thence through the upper terminal limit switch 66 and thence through the lower terminal limit switch 68 and thence through the car safety switch 70 to the controller terminal contact 48. The contact terminals 46-48 of the controller switch are interconnected by a conductor 72, and hence the second control circuit continues on through terminal 46 and through conductor 74 to a second normally open contact 76 of the sequence relay switch 60. Another conductor 78 leads from the contact 76 to the terminal armature 79 of a two-way normally open motion responsive switch 80. The armature of the switch 80 is connected such as by means of a friction coupling device 81 of the fluid coupling type to a shaft 82 which is in turn geared to the elevator traction sheave shaft as by means of a sprocket-chain system 84. Hence, whenever the elevator traction sheave shaft is rotating in one direction the armature of the switch 80 will be thrown over against one of either of the contact terminals 86-88 of the switch, while upon reversal of the direction of shaft rotation the switch armature will be thrown over against the other contact terminal of the switch. However, when the shaft is stopped the armature of the switch 80 moves to its neutral or non-contacting position, as under the influence of spring means 89.

Thus, it will be seen that when the car controller 40 is in its neutral position, as shown in the drawing, the segment 42 thereof interconnects the contacts 44-46-48 thereby creating a control feed from either terminal 46 or 48 to terminal 44 which is connected through conductor 90 to the relay coil 62 of the sequence control switch 60. Thus, when all of the hatchway doors and the elevator gate are closed (with the car controller in neutral position) the relay coil 62 is energized and lifts the switch device 60 so as to bridge the contacts thereof. By means of the lower pair of contacts of the switch the circuit of the relay coil 62 remains energized and the relay switch holds itself closed, while the bridging of the upper pair of contacts of the relay switch provides feed for the motor control relay coils 92-94-96.

Thus, if the car controller handle 40 is moved over to the "up" position the segment 42 will clear the contacts 44-46 and will interconnect the contact 48 with another contact 100, thereby providing a closed circuit from terminal 100 through conductor 102, and thence through the upper normal limit switch 104 and thence to contact 106 of a normally closed relay switch 108 and thence through the relay coil 92 of a relay switch 110. This will energize the coil 92, thereby lifting the relay switch 110, whereupon the upper power control contacts thereof will close. At the same time the auxiliary contacts at the bottom of the switch 110 will close, providing a closed circuit to the relay coil 96 on the relay switch 112. This lifts the switch 112, whereupon it will be seen that the power control contacts of switches 110-112 are both closed, whereby a three phase power supply is established to the motor 30 through power conductors 113-114-115. The motor will thereupon turn to drive the elevator sheave 14 to raise the elevator car, the motor torque being

transmitted through the fluid coupling 25. The fluid coupling device 25 thereupon operates to provide a particularly "soft" acceleration effect because of its inherent tendency to slip at slow speeds and to gradually increase in torque transmitting efficiency as the speed increases.

As illustrated in the top center portion of the drawing, the electro-magnetic brake device 32 is automatically energized coincidentally with energization of the motor 30 through conductors 116-117 leading from two of the motor terminals. The conductors 116-117 connect to a rectifier 118, the output terminals of which connect through conductors 120-121 to the coil of the electromagnetic brake device 32, whereby D. C. current is supplied to the brake coil whenever the motor 30 is energized. The brake device 32 comprises, for example, a spring-actuated friction band or block brake with the coil magnet thereof arranged to release the brake whenever the motor 30 is energized. Thus, the brake device 32 automatically sets whenever the power to the motor is interrupted.

The upward travel of the elevator car may, of course, be interrupted either by contact of any suitable member extending from the car, such as a cam, with the upper normal limit switch arm, or by manual movement of the control handle 40 away from its "up" position. Assuming, for example, the control handle to have been returned by the operator to its neutral position, the feed through the segment 42 between the contacts 48-133 is thereby interrupted, and the circuit including the coil 92 in the up travel relay unit is now deenergized. Momentarily, however, the inertia of the car and the drive mechanism will continue the upward travel of the car, and therefore the armature of the traction switch 80 is still biased to keep the "up" travel contacts closed. Thus, the feed from the controller contact 46 forms a closed circuit through the conductors 74-78 and the traction switch 80 and the conductor 124 and the contact 128 of the relay switch 110. As the switch 110 drops, due to deenergization of the coil 92 as explained hereinabove, the circuit through the contact 128 is thereupon completed through switch contact 128, conductor 130, controller contact 132, and thence through the lower normal limit switch 134, and then back through conductor 136 through contacts 138-139 of the relay switch 110, to the coil 94 of the down control relay switch 108, and thence through contacts 148-56 of the switch 60 and thence through conductor 50 to the supply main 35.

Thus, the down control relay switch 108 and the main line conductor switch 112 are both lifted, thereby completing a three-phase power supply to the motor 30, but in reverse phase relationship to the direction of the previous operation of the motor. The motor is thereby "plugged" or reversed, and drags upon the elevator drive mechanism to decelerate the latter in the manner of a braking device; the traction coupling device 25 permitting varying rates of slip between the motor and the elevator traction sheave, depending upon the relative speeds thereof.

It is with respect to this braking performance of the motor 30 during deceleration of the elevator car travel that the novel torque transmitting characteristics of the traction coupling device, such as for example of the so-called "fluid coupling" type, become manifest and provide an improved electrical braking or "plugging" performance when using a motor of the relatively

economical single speed A. C. type. For example, when the controller is moved to neutral position the driving mechanism is at first traveling at relatively high speed, and the tendency of the traction sheave end of the drive mechanism to overrun the motor end of the mechanism is at first strenuously resisted because of the nature of the operation of the fluid coupling device at high speeds. Thus, at this stage the motor imposes a high degree of drag upon the drive mechanism, thereby tending to quickly brake the car travel. However, as the rate of car travel is reduced, the coupling 25 becomes less efficient as a torque transmitter, and a progressively softening dragging effect is supplied by the motor to the traction sheave; with the result that as the elevator car slows down and approaches the stop the deceleration rate smooths off, thereby avoiding violent deceleration shock in connection with the stopping operation.

In event the inertia of the elevator car and driving mechanism is sufficient to continue to carry the car upward even after the motor 30 comes to a stop, the motor will of course then commence to rotate in reverse direction, thereby maintaining a relative speed between the driving and driven elements of the traction coupling 25 so as to continue to impose the desired braking drag upon the traction sheave end of the mechanism. In any case when the traction sheave is brought to rest the traction switch 80 will open, thereby interrupting the circuit to the contact 106 and the circuit to the relay switch coil 94, permitting the switch 108 to drop. This interrupts the power supply to the motor and to the electro-magnetic brake 32, whereupon the latter is mechanically applied to hold the elevator car at rest.

It will be appreciated that if, instead of manual return of the controller to neutral position as explained hereinabove, the elevator car is permitted to rise until the car cam opens the upper normal limit switch 104, the circuits to the coil 92 of the switch 110 will be interrupted; and that the switch 80 will thereupon assume control of the system to cause reversal of the motor so as to effect the braking action explained hereinabove and to finally stop the elevator car with the mechanical brake applied.

Downward car travel control is effected by the mechanism illustrated upon manual manipulation of the controller 40 into its "down" position as shown in the drawing, whereupon the control circuits are completed to energize the "down relay" and the main line switch 112 to complete a three-phase power supply to the motor in reversed phase relation. The switch 80 then closes in the down direction upon starting of the elevator travel upon centering of the car control handle 40, or opening of the lower normal limit switch 134, the relays 108-112 will be deenergized, whereupon control circuit feed will be established through switch 80 and conductor 145 to the coil 92 of the "up relay" 110, which will in turn energize relay 112 and cause the motor to be "plugged." The elevator mechanism will be thereby braked as explained hereinabove until it comes to rest at which time the armature of switch 80 assumes its neutral position. The control circuit feed is then broken to the "up relay" 110, which then falls out and deenergizes the motor 30 and causes the brake 32 to be set.

Thus, it will be understood that it is a particular feature and advantage of the invention that acceleration of the elevator car travel is acquired through a traction-type coupling which prevents

violent acceleration effects, and that braking of the car travel is acquired by "plugging" the single speed A. C. motor and transmitting the drag therefrom to the elevator traction sheave through the traction coupling device which delivers in improved manner a counter-torque operating to retard and stop the car. Thus, a nearly constant rate of deceleration is obtained, and although the driving motor may even be running in reverse direction when bringing the elevator car to a stop, no violent deceleration effects are experienced, and the car comes to a "soft" stop because of the braking characteristics of the "plugged" motor operating in cooperation with the novel coupling element of the driving system.

What is claimed is:

1. In an elevator drive and braking control system, a reversible alternating current electric motor, an elevator drive shaft, a fluid coupling device interconnecting the drive shaft of said motor and said elevator drive shaft, and a power supply control system for said motor including manual switch means operable to cause energization of said motor, switch means operable to reverse said motor to impose a counter-torque through said coupling device to halt the elevator travel, and means operable automatically upon halting of said travel to deenergize said motor.

2. In combination, an elevator, a reversible alternating current electric motor, a traction type coupling device interconnecting the drive shaft of said motor and said elevator for moving the latter, and a power supply control system for said motor including manual switch means operable to start said motor to run in either direction and operable to reverse said motor while running to impose a counter-torque through said traction coupling device to halt the elevator travel, and switch means operable automatically upon halting of said travel to deenergize said motor.

3. In an elevator drive and braking control system, a reversible alternating current electric motor, an elevator drive shaft, a fluid coupling device interconnecting the drive shaft of said motor and said elevator drive shaft, and a power supply control system for said motor including manual switch means operable to cause energization of said motor, switch means operable to reverse said motor when running to impose a counter-torque through said coupling device to halt the elevator travel, and means operable automatically upon halting of said travel to deenergize said motor.

4. In an electric drive and braking system for elevators, a reversible alternating current motor, an elevator drive member, a traction type coupling device interconnecting the drive shaft of said motor and said elevator drive member, and a power supply control system for said motor including switch means operable to cause energization of said motor, switch means operable to reverse said motor when running to impose a counter-torque through said traction coupling device to brake the elevator travel, and means operable automatically upon halting of said travel to deenergize said motor.

5. In an elevator drive and braking control system, a reversible alternating current electric motor, an elevator drive shaft, a fluid torque converter interconnecting the drive shaft of said motor and said elevator drive shaft, and a power supply control system for said motor including manual switch means operable to cause energization of said motor, switch means operable to reverse said motor to impose a counter-torque

through said converter to halt the elevator travel, and means operable automatically upon halting of said travel to deenergize said motor.

6. In combination, an elevator, a reversible alternating current electric motor, a torque converter coupling device interconnecting the drive shaft of said motor and said elevator for moving the latter, and a power supply control system for said motor including manual switch means operable to start said motor to run in either direction and operable to reverse said motor while running to impose a counter-torque through said traction coupling device to halt the elevator travel, and motion responsive switch means operable automatically upon halting of said travel to operate to cause deenergization of said motor.

7. In an elevator drive and braking control system, a reversible alternating current electric motor, an elevator drive shaft, a fluid torque converter interconnecting the drive shaft of said motor and said elevator drive shaft, and a power supply control system for said motor including manual switch means operable to cause energization of said motor, switch means operable to reverse said motor when running to impose a counter-torque through said converter to halt the elevator travel, and means operable automatically upon halting of said travel to deenergize said motor.

8. In an electric drive and braking system for elevators, a reversible alternating current motor, an elevator drive member, a fluid torque converter device interconnecting the drive shaft of said motor and said elevator drive member, and a power supply control system for said motor including switch means operable to cause energization of said motor, switch means operable to reverse said motor when running to impose a counter-torque through said fluid torque converter to brake the elevator travel, and means operable automatically upon halting of said travel to deenergize said motor.

9. In an elevator drive and braking control system, a reversible alternating current electric motor, an elevator drive shaft, a torque connector interconnecting the drive shaft of said motor and said elevator drive shaft, and a power supply control system for said motor including manual switch means operable to cause energization of said motor, switch means operable to reverse said motor to impose a counter-torque through said connector to halt the elevator travel, and means operable automatically upon halting of said travel to deenergize said motor.

10. In combination, an elevator, a reversible alternating current electric motor, a torque connector device interconnecting the drive shaft of said motor and said elevator for moving the latter, and a power supply control system for said motor including manual switch means operable to start said motor to run in either direction and operable to reverse said motor while running to impose a counter-torque through said connector device to halt the elevator travel, and switch means operable automatically upon halting of said travel to deenergize said motor.

11. In an electric drive and braking system for elevators, a reversible alternating current motor, an elevator drive member, a hydrokinetic fluid coupling device interconnecting the drive shaft of said motor and said elevator drive member, and a power supply control system for said motor including switch means operable to cause energization of said motor, switch means operable to reverse said motor when running to impose a

counter-torque through said coupling device to
brake the elevator travel, and means operable
automatically upon halting of said travel to
deenergize said motor.
